HAIR WAVING PAD

Fred Hauser, White Plains, N. Y.

Application May 11, 1933, Serial No. 670,442
Renewed March 12, 1935

1 Claim. (Cl. 132—36.2)

One object of this invention is the provision of a novel type of pad adapted to be wound about a lock of hair in the process of hair-waving prior to the application of steam thereto. This pad is so designed and constructed as to be efficient for the purpose mentioned and to require a minimum of skill and time in its application.

The above and other objects will become apparent in the description below, in which characters of reference refer to like-named parts in the drawing.

Referring briefly to the drawing, Figure 1 is a plan view of the pad, prior to its use.

Figure 2 is a cross-sectional view taken on the line 2—2 of Figure 1.

Figure 3 is a view illustrating the first step in wrapping the pad about a lock of hair.

Figure 4 is a similar view illustrating an intermediate step.

Figure 5 is a similar view showing the pad wrapped about the hair.

Referring in detail to the drawing, the numeral 10 represents a substantially rectangular sheet of tin-foil or the like superimposed upon a sheet of waxed paper 11 of the same dimensions. Both these sheets are continued on one side to provide a tongue 12 formed of the same two layers, that is, tin foil and wax paper, this tongue being also rectangular in form. On their long edges opposite the tongue 12, the sheets 10 and 11 are sewed together or joined in any other suitable manner. This entire side (left hand, Figure 1) of the pad is represented by the numeral 13, the seam uniting the two layers thereof being indicated at 14.

Also joined by said seam 14, and hence to the side 13 of the pad, are the adjacent edges 15 and 16 of a folded-over sheet of gauze 17. A strip of flannel or similar material 18 lies between the folds or layers of the gauze 17, its dimensions being smaller than those of the gauze layers. This flannel strip 18 is also sewed in the seam 14. The edge of the gauze 17 opposite the seam 14, is extended on one end to form a tongue 19 of the same dimensions and outline as the tongue 12, a cut-out or recess 20 separating the two tongues 12 and 19. The right hand side, Figure 1, of the pad is indicated by the numeral 21.

A conventional curling rod is shown at 22, having the hair 23 wound thereon, the end 24 of the curl of hair extending at an angle from the tip of the rod, the hair being retained thereon and

the end 24 being retained at its angle to the rod, by the cord 25.

In applying the pad to the hair, the outer edge of the side 21 is aligned with the curl of hair as shown in Figure 3, and the gauze tongue 19 is folded down about the base of the hair end 24. The remainder of the side 21 is then wrapped around the hair 23, by either rolling the rod 22 toward the right, Figure 3 or wrapping the pad thereon in the opposite direction. This rolling or wrapping continues until the entire side 21 has been wrapped about the hair, together with the entire side 13, the tin foil layer 10 of the latter being on the outside of the wrapping. Finally, the tongue 12 is wrapped about the gauze-covered base of the hair end 24. Hence the entire curl of hair is wrapped, with the tin foil covering the wrapping.

With the curl of hair thus wrapped, a steam pipe represented simply for illustration and indicated in dotted lines by the numeral 22', is slid over the wrapper until its upper end is checked by the base of the wrapped hair end 24. Thus slipping of the pipe 22' over the end of the hair is prevented, so that the end may be gripped later to remove the pipe. The steam flowing from the pipe surrounds the wrapping, which it penetrates, so that after an interval of time the hair becomes moist, and the pipe is removed.

The layer 10 of tin foil, which forms the outer shell of the wrapping, serves to form a substantially solid mass of the curl of hair, approaching the equivalent of a semi-rigid shell, thus eliminating the necessity of tying the wrapping about the hair.

Obviously modifications in form and structure may be made without departing from the spirit and scope of the invention.

I claim:

A hair waving pad comprising a pair of substantially rectangular members of like dimensions joined together edge to edge by a seam or the like, each of said members having an extension forming a tongue, said tongues extending from opposite extremities of the same side of the pad to form a recess therebetween, one of said members being formed of two layers of gauze with a sheet of flannel therebetween, the other member being formed of a layer of waxed paper and a layer of tin foil.

FRED HAUSER.
